UNITED STATES PATENT OFFICE.

SEWARD J. DICK, OF CLYMER, PENNSYLVANIA.

CURTAIN AND SHADE SUPPORTING BRACKET.

Application filed September 13, 1924. Serial No. 737,556.

To all whom it may concern:

Be it known that I, SEWARD J. DICK, a citizen of the United States, residing at Clymer, in the county of Indiana and State 5 of Pennsylvania, have invented new and useful Improvements in Curtain and Shade Supporting Brackets, of which the following is a specification.

The object of my said invention is the 10 provision of curtain and shade supporting brackets possessed of practical advantages as hereinafter set forth.

To the attainment of the foregoing, the invention consists in the improvement as 15 hereinafter described and definitely claimed.

In the accompanying drawing, forming part of this specification:—

Figure 1 is a broken elevation showing my novel brackets in use.

20 Figure 2 is a top plan view showing one of the brackets and portions of poles carried thereby.

Figure 3 is a perspective of the other brackets—i. e., the left hand bracket in 25 Figure 1.

Figure 4 is a perspective of the right hand bracket—i. e., the bracket shown in Figure 2.

Figure 5 is a view showing in plan the blank form which the left hand bracket is 30 formed, it being understood in this connection that the blank for the right hand bracket is similar except that it has a notch in lieu of a circular aperture.

Similar numerals of reference designate 35 corresponding parts in all of the views of the drawing.

I show in Figure 1 a window casing 1, a shade 2, and curtain supporting poles 3, the said poles being provided at their ends with 40 angularly disposed flattened arms adapted to be arranged in slotted portions of my novel brackets as hereinafter set forth.

Each of my novel brackets is formed of 45 a single piece of sheet steel or other material appropriate to its purpose, the sheet being stamped as shown in Figure 5, and being then manipulated so that each bracket comprises a body 4 adapted to rest in parallelism with the face of the casing 1 and 50 against such face and having a loop 5 across its upper end and also having at the ends of the loop widely separated depending barbs 6. Manifestly the said loop 5 is adapted to be arranged on the upper edge of the 55 window casing 1, and the barbs 6 are adapted to be embedded in said edge to strongly

connect the bracket of itself to the casing and so that the weight imposed on the bracket will tend to anchor the same in place. The body 4 of each bracket is provided with an 60 intermediate portion 7 of reduced width, forming a shank and in addition to the body 4 with its shank 7 each bracket comprises forwardly reaching parallel arms 8 at opposite sides of the portion 7 and a forwardly 65 reaching arm 9, the said arm 9 being carried by a body portion 4^x at one side of the reduced portion 7, and the arm 9 of the left hand bracket being provided with a circular aperture 10 while the arm 9 of the right 70 hand bracket is notched as designated by 11.

The forwardly reaching arms 8 of each bracket are slotted at 12 to receive the arms of the poles 3 in the manner illustrated in Figure 2, so that the poles 3 will be strongly 75 engaged with and supported by the brackets without the assistance of extraneous means.

The arms 9 of the brackets carry roller of the shade 2 in the ordinary well known manner.

It will be apparent from the foregoing that my novel brackets are susceptible of ready application and adjustment without the employment of skilled labor and that they are adapted to carry both a shade and 85 poles or rods 3; and it will be also understood that the elements 3 may when desired be in the form of double rods one for curtains and the other for drapery. It will also be appreciated that the barbs 6 of each 90 bracket are widely separated and hence are adapted to prevent the brackets from swinging sidewise.

In addition to the advantages ascribed to my novel brackets it will be noted that the 95 brackets are susceptible of being economically manufactured and that by reason of the disposition of their several portions they are adapted to sustain considerable weight.

I have specifically described the preferred 100 embodiment of my invention in order to impart an exact understanding of said embodiment. I do not desire, however, to be understood as confining myself to the construction disclosed inasmuch as my invention 105 is defined by my appended claim within the scope of which changes may be made without departure from my invention.

Having described my invention, what I 110 claim and desire to secure by Letters-Patent, is:—

As a new article of manufacture, a bracket

for a shade and pendent drapery comprising a body having a reduced intermediate imperforate portion and a laterally extending portion below and at one side of said 5 intermediate reduced portion, pendent barbs at the upper end of the body, slotted arms reaching forwardly from the opposite ver-

tical edges of the reduced portion of the body, and an arm reaching forwardly from the outer end of the lateral portion of the 10 body and adapted to support a shade.

In testimony whereof I affix my signature.

SEWARD J. DICK.
